BURGLARPROOF LOCK

James Joseph Walsh, Baltimore, Md.

Application July 31, 1947, Serial No. 764,979

4 Claims. (Cl. 109—32)

1

This invention relates to locks for doors and the like, and its object is to provide an improved lock which is capable of releasing a charge of gas whenever any attempt is made to force it.

The invention resides in an improved lock having a bolt which may be manipulated with perfect safety by using the proper key, but which will actuate a certain mechanism for discharging a noxious gas whenever sufficient force is applied to the lock to cause the bolt to move laterally or to bend. The person forcing the lock is repelled or overcome by the gas before the bolt is forced from its socket.

The present device is an improvement over applicant's prior invention, United States Patent No. 1,758,096. The invention involves improved means for actuating the gas discharging means, as well as an improved type gas container and release device which is safe to install and which will stand considerable jarring, as may occur in slamming the door, without being set off.

A further improvement involves a lock adapted for use with sliding doors or with double swinging doors or others found in garages, warehouses, etc.

It is, therefore, an object of the present invention to provide an improved burglar-proof lock which releases a noxious gas when forced, but does not do so when key actuated in the proper manner.

It is a further object of the present invention to provide an improved burglar-proof lock adapted for use on sliding doors or double doors, which will release noxious gas when forced, but not when properly key actuated.

It is a further object of the present invention to provide an improved burglar-proof lock adapted to release noxious gas when forced, but which will not otherwise release noxious gas even under substantial shock.

These and other objects of the present invention are attained by the device of the present invention, preferred embodiments of which are illustrated in the accompanying drawings, wherein:

Figure 1 is a perspective view, partially fragmentary, of a door having installed thereon one embodiment of the improved lock, and;

Figure 2 is an elevation of the mechanism of the lock shown in Figure 1, with the cover plate removed, and;

Figure 3 is a section taken on the lines 3—3 of Figure 2, and;

Figure 4 is a side elevation, partly in section, of the lock shown in Figure 1, wherein the principal parts are unassembled; and

2

Figure 5 is a perspective of an alternative form of the lock shown in Figure 1, installed on double doors, fragments of which are shown.

Referring to Figure 1, there is shown one embodiment of the lock, comprising a cover plate 10 and a back plate 11. Protruding through a fragment of the door 12 is the face of a conventional lock barrel 13. Bolt 15 is shown in the extended or locked position, where it is adapted to contact a socket, not shown, which is attached to the door jamb in the customary manner. The back plate 11 contains two apertures 16, through which the gas may escape into an aperture 17 in the door, which opens out on the edge of the door so that gas can escape. These apertures are shown to be rectangular, but may just as well be round.

With reference to Figure 2, there is shown an elevational view of the lock with the cover plate 10 removed. Bolt 15 has integrally attached thereto a bolt plate 18 containing an elongated slot 20 and carrying an inwardly extending flange 19a. Pivotally attached to the bolt plate is a tumbler 21, attached to one end of which is a leaf spring 22 adapted to contact bolt 15 to urge the tumbler upwardly. An arm 24, which is adapted to oscillate when actuated by a key and which depresses the tumbler 21, moves bolt plate 19 by means of abutments 25 thereon in the customary manner for key actuated locks of the type.

An important feature of the present invention is the provision of two springs attached to back plate 11 and about which the slot 20 reciprocates in the ordinary action of the bolt. A side view of these springs is shown in the section in Figure 3. Spring 27 is a spiral spring which is secured in adjustable relationship to back plate 11 by a set screw 28. It may be provided with a washer 29, as illustrated, to aid in retaining the spring, and there is also provided a lower washer 30 which frictionally engages bolt plate 19 as it reciprocates, and the spring acts to keep the bolt plate against the back plate. Spiral torsion spring 32 is mounted on a rectangular abutment 33 which extends through guide slot 20. The spring is adjustably attached to the abutment by set screw 34. One end of the torsion spring engages a hammer 36, while the other end may be looped around spring 27. The hammer is pivotally mounted on the screw 34 and is maintained in the upright or cocked position by means of ledge 37 which may be integrally formed on the back plate. The flange 19a on the plate 18 is adapted to engage the hammer 36 when the latch bolt is moved laterally.

The back plate contains a number of ears 40, which are adapted to engage the cover plate and which may contain holes for screws or other attachments thereto.

One edge of bolt plate 19, several of the ears 40, and the cover plate 10 all serve to define a space within which is placed the bomb container 41. For easy removal and replacement, it is preferable that this bomb container be substantially rectangular so as to substantially fill the space as provided, and be retained in position therein without attachment directly to any part of the lock. Pivotedly attached to the top of the bomb container 41 is a firing pin 42 which engages an explosive cartridge 43. The explosive cartridge 43, when set off, has its force retained in the bomb container 41, which is preferably of a metal such as steel. A cylinder of noxious gas 44 in the bomb container is pierced by a fragment of the explosive cartridge. This cylinder may be of metal such that it will withstand substantial shock which may be caused by slamming the door, and is not easily set off by any such shock, including that which might be encountered in handling the device. Its walls, however, are just sufficiently thin that they will be pierced by a part of the explosive cartridge. It will be seen that in transporting or installing the device, the firing pin 42 may be swung away from contact with the cartridge, and may be placed on top of the cartridge only when the lock is assembled for actual use. The metal cylinder is also particularly advantageous because it can retain gas under high pressure for long periods of time.

Figure 4 is a side elevation, partly in section, showing the principal parts of the lock in un-assembled relationship. This view also shows an additional lock barrel 51 so that the lock may be operated by a key from the inside, as well as from the outside.

Figure 5 is a perspective view of an alternative form of the lock shown in Figure 1, which may be installed on double doors 45 and 46. A clasp 47 is welded or otherwise attached to the bolt 15, and a chain 48 attached to a hasp 49 by means of a padlock 50 provides the connection between the two doors. It will be seen that if the lock is installed on the inside of the door, and an attempt is made to force the door open from the outside, the chain will cause a lateral movement of the bolt to set off the noxious gas. In this use of the lock, it is not necessary to use the barrel locks, but the lock is still controlled by a key which is used in the padlock instead. This arrangement may as well be used on other doors that do not swing against a door jam, as for example, sliding doors or overhead doors, such as are found in garages, warehouses, etc.

It will be understood that the noxious gas to be used may be any one of a number of gases, but the invention is particularly adapted to tear gas.

It will be seen that in the ordinary operation of the lock shown in Figures 1 to 4 inclusive, a key will be used to move the bolt into or out of locked position, but in unauthorized use, when pressure is applied against the door, the bolt plate 19 will be pressed outwardly against spring 27 so that the hammer 36 is engaged by the flange 19a and forced off the edge of abutment 31 and by the spring means strikes the firing pin which sets off the explosive cartridge, which in turn breaks open the cylinder of noxious gas. The gas passes out through the aperture in the edge of the door such that the person will be affected

without being able to stop the flow of the gas. In this manner the gas is released even before sufficient pressure is used to actually break the lock open.

The new and improved lock entails a number of advantages not found in the prior art. For example, the helical torsion spring actuating the hammer takes a minimum of space for operation, has an adjustable tension, has the double function of actuating the hammer as well as retaining the hammer against the abutment, and allows a wide arc to attain great force before striking the firing pin.

The new and improved bomb container provides a permanent, easily replaceable, and substantially shock-proof container for the noxious gas. The pivoted firing pin on the cartridge prevents accidental discharge in transportation or installation. In addition, the cartridge is very easily replaced since it is not rigidly anchored within the lock.

The alternative arrangement using the chain device permits the use of the burglar-proof key-controlled tear gas lock on doors not adapted to the first embodiment, and including double swinging, sliding, and overhead doors such as are commonly found in garages, warehouses, etc.

While particular embodiments of the invention are illustrated and described herein, other modifications may be made without departing from the spirit of the invention.

What is claimed is:

1. A burglar-proof lock comprising a noxious gas-filled closed receptacle, an explosive charge, a firing pin adapted to set off said explosive charge and rupture said receptacle to discharge gas from the receptacle, a hammer for contacting the firing pin, spiral torsion spring means for causing said hammer to strike said firing pin, means for normally retaining said hammer out of contact with said firing pin, a bolt adapted to reciprocate in said lock, a bolt plate integrally joined to said bolt and formed with a guide slot, guide means cooperating with said slot, means for causing the release of said hammer by lateral movement of said bolt, coil spring means for normally resisting lateral movement of said bolt, said spiral torsion spring means also supplementing said coil spring means in resisting lateral movement of said bolt, and means for adjusting the tension on each of said springs.

2. A burglar-proof lock comprising a noxious gas-filled closed receptacle, an explosive charge, a firing pin adapted to set off said explosive charge and rupture said receptacle to discharge gas from the receptacle, a hammer for contacting the firing pin, spiral torsion spring means for causing said hammer to strike said firing pin, means for normally retaining said hammer out of contact with said firing pin, a bolt adapted to reciprocate in said lock, a plate carried by said bolt and formed with an inwardly extending flange adapted to engage said hammer, said hammer being releasable by lateral movement of said bolt, and additional coil spring means for normally resisting lateral movement of said bolt with said spiral torsion spring means also resisting such lateral movement.

3. A burglar-proof lock comprising a noxious gas-filled closed receptacle, an explosive charge, a firing pin adapted to set off said explosive charge and rupture said receptacle to discharge gas from the receptacle, a hammer for contacting the firing pin, spiral torsion spring means for causing said hammer to strike said firing pin,

means for normally retaining said hammer out of contact with said firing pin, a bolt adapted to reciprocate in said lock, a bolt plate integrally joined to said bolt and having an inwardly extending flange adapted to engage said hammer, said bolt plate being formed with a guide slot, guide means cooperating with said slot, said hammer being releasable by lateral movement of said bolt, and coil spring means for normally resisting lateral movement of said bolt, the first said spring means also urging said hammer against said hammer retaining means to normally prevent release thereof.

4. In combination, a door and a burglar-proof lock, said lock normally adapted to retain said door in locked position and to release noxious gas when great pressure is exerted against said door, said burglar-proof lock comprising a noxious gas-filled closed receptacle, an explosive charge, a firing pin adapted to set off said explosive charge and rupture said receptacle to discharge gas from the receptacle, a hammer for contacting the firing pin, spiral torsion spring means for causing said hammer to strike said firing pin, means for normally retaining said hammer out of contact with said firing pin, a bolt adapted to reciprocate

in said lock, a bolt plate carried by said bolt and having a flange adapted to engage said hammer, said bolt plate being formed with a guide slot, a backing plate having an abutment extending through said slot and carrying said spiral torsion spring means, said hammer being releasable by lateral movement of said bolt, and coil spring means for normally resisting lateral movement of said bolt with said coil spring means being supplemented by said spiral torsion spring means.
